[57] CLAIM

The ornamental design for a wheel cover, as shown and described.

DESCRIPTION

FIG. 1 is a front perspective view of a wheel cover in accordance with applicant's design;

FIG. 2 is a rear perspective view thereof;

FIG. 3 is a bottom perspective view thereof, top and side perspective views corresponding thereto, except for omission of the air stem aperture arrangement shown centrally in FIG. 3; and

FIG. 4 is a perspective view seen from below and to the front thereof.

The broken lines in the drawing are for illustrative purposes only.

FIG. 1

FIG. 2

FIG. 3

FIG. 4
